(57) **CLAIM**

The ornamental design for an electronic device, as shown and described.

DESCRIPTION

FIG. 1 is a perspective view of an electronic device showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of the electronic device shown in an alternate configuration with the camera flipped up;

FIG. 9 is a front view thereof;

FIG. 10 is a rear view thereof;

FIG. 11 is a left side view thereof;

FIG. 12 is a right side view thereof;

FIG. 13 is a top view thereof;

FIG. 14 is a bottom view thereof;

FIG. 15 is an enlarged view of a portion of the electronic device of FIG. 1;

FIG. 16 is an enlarged view of a portion of the electronic device of FIG. 2;

FIG. 17 is an enlarged view of a portion of the electronic device of FIG. 8; and,

FIG. 18 is an enlarged view of a portion of the electronic device of FIG. 9.

The evenly-dashed lines shown in the drawings depict portions of the electronic device that form no part of the claimed design. The dash-dot-dot lines enclosing portions of the claimed design that are illustrated in enlargements form no part of the claimed design.

1 Claim, 14 Drawing Sheets
